HIS ATTORNEY

UNITED STATES PATENT OFFICE.

LEO PRANGE, OF BROOKLYN, NEW YORK.

DESIGN FOR A BUTTON.

SPECIFICATION forming part of Design No. 21,317, dated January 26, 1892.

Application filed December 18, 1891. Serial No. 415,551. Term of patent 3½ years.

To all whom it may concern:

Be it known that I, LEO PRANGE, of Brooklyn, Kings county, and State of New York, have originated and produced a new Design 5 for Buttons, of which the following is a specification.

I will describe a button embodying my design.

In the accompanying drawings, Figure 1 is 10 a front view of a circular button embodying my design. Fig. 2 is a perspective side view thereof.

My design comprises a circular figure A and a substantially triangular figure B, having one 15 of its points or angles meeting the circular figure. The border-line of the circular figure may be formed of figures representing small jewels. Within this border-line are three leaf-like or petal-like figures C, which radiate 20 from the lower portion of the border-line. A

small jewel-like figure D is formed below these leaf-like or petal-like figures C. Within the border-line of the circular figure A and intermediate of the leaf-like or petal-like figures C, I have shown filigree-work.

The surface of the button intermediate of the circular figure A and the rectangular figure B is shown as covered with wavy lines.

What I claim, and desire to secure by Letters Patent, is—

The design for a button, as herein shown and described.

In testimony whereof I have signed my name to this specification in the presence of two subscribing witnesses.

LEO PRANGE.
